Inventor:
Arthur C. Boyd

By Grover Elliott
Attest.

UNITED STATES PATENT OFFICE.

ARTHUR C. BOYD, OF MAYWOOD, ILLINOIS.

LIQUID-FUEL ATOMIZER.

Application filed November 1, 1923. Serial No. 672,075.

This invention relates to a liquid fuel atomizer and concerns itself with a structure comprising a stack of loosely piled and very thin rings arranged in superposed relation, together with means for imparting a high rate of rotation to said structure whereby sufficient centrifugal force is produced for atomizing a weak or dripping flow of liquid fuel.

10 The invention comprises the novel structure and combination of parts hereinafter described and more particularly pointed out and defined in the appended claims.

In the accompanying drawings, which illustrate a preferred embodiment of this invention and in which similar reference numerals refer to similar features in the different views, Fig. 1 is a vertical sectional view through a liquid fuel atomizer involving this 20 invention.

Fig. 2 is a sectional view taken upon the line 2—2 of Fig. 1.

Fig. 3 is an enlarged fragmentary sectional view through a stack of atomizing rings involving this invention.

In the chosen embodiment of this invention there is shown an atomizer 47 consisting of a casing section 51 which is closed by a cover 48 that telescopes over the upper portion 30 of the casing section. The casing section is provided with a radially extending flange or seat 47^a upon which a stack of exceedingly thin atomizing rings 28 are supported. The atomizing rings are preferably 35 flat and they are loosely arranged upon one another so that adjacent rings normally contact each other. The outer periphery of each ring is preferably of a converging nature and comes to a point as indicated at 23 in Fig. 3. The width of each ring should preferably be 40 about two and one-half thousandths of an inch (.0025) in thickness. The afore-mentioned cover 48 is retained in position by a pair of bolts 49 which extend through the 45 bottom of the casing. The lower ends of these bolts are equipped with adjustable nuts and the edge of the telescoping flange of the cover is located directly above the stack of atomizing rings 28. It will be appreciated 50 that by adjusting the nuts it is possible to vary the ring space in order to provide for the proper separation of the rings during the atomizing operation. Usually a very minute separation of the atomizing rings is all that 55 is required. However, by properly adjust-

ing the cover the degree of separation of the rings may be varied to suit the exigencies of a particular case.

It will be noted that the casing 51 is provided with concave recesses and slots 50 through which the liquid fuel is adapted to be expelled from the interior of the casing. Any means may be provided for supplying fuel to the interior of the casing. In the present instance, there is shown a supply pipe 53 extending into the casing. The supply pipe is shown as extending through a hollow shaft 52 upon the casing section 51. This hollow shaft 52 affords a means for rotating the casing at a sufficiently high rate of 65 speed for producing the desired centrifugal force.

In the operation of this invention it is contemplated that the fuel may be supplied in a slow or weak stream or what may be 75 termed a dripping stream, so that there is seldom any appreciable quantity of fuel in the casing. Under such conditions the casing with the atomizing rings is rotated very rapidly for producing sufficient centrifugal 80 force for expelling the liquid fuel through the slots 50 and between adjacent atomizing rings, which are susceptible of minute separation according to the adjustment of the cover element 48. Under a very fine adjustment, the liquid fuel will be very thoroughly 85 and minutely atomized and will emerge from the outer peripheries of the ring in the form of a mist or fog.

While I have not illustrated any particular 90 manner in which this atomizer may be utilized, it will be appreciated that it will find ready application in internal combustion engines, liquid fuel heaters and any apparatus requiring the atomization of liquid 95 fuel.

I am aware that numerous details of construction may be varied without departing from the principles of this invention, and I do not propose limiting the patent otherwise 100 than necessitated by the prior art and the appended claims.

Having described my invention, what I claim and desire to secure by Letters Patent is:

1. A liquid fuel atomizer comprising a rotatable member, a plurality of very thin rings in superposed relation on said member, adjacent rings being normally in contact 110 with each other, means for confining said

rings for minute separation and means for supplying a stream of liquid fuel interiorly of said rings.

2. A liquid fuel atomizer comprising a rotatable member, a plurality of very thin rings in superposed relation on said member, adjacent rings being normally in contact with each other and each ring having a converging periphery, means for supplying a stream of liquid interiorly of said rings and means for rapidly rotating said member for the purpose set forth.

3. In a liquid fuel atomizer a casing having an annular seat, a stack of thin atomizing rings loosely piled in superposed relation upon said seat, adjacent rings being normally in contacting relation, adjustable

means for varying the confining space of said rings and for allowing minute separation of said rings, means for supplying liquid fuel interiorly of said rings and means for rotating said casing.

4. A liquid fuel atomizer comprising a rotatable member and a stack of atomizing rings substantially two and one-half (.0025) thousandths of an inch in thickness, arranged in superposed relation with adjacent rings in contact with each other, supported by said member and means for supplying liquid fuel interiorly of said rings.

In witness whereof, I have hereunto set my hand this 30th day of October, 1923.

ARTHUR C. BOYD.
